EARTHMOVING TRACTOR AND PUSHER COMBINATION

David L. Painter, Evanston, Ill., assignor to LeTourneau-
Westinghouse Company, Peoria, Ill., a corporation of
Illinois

Application March 18, 1957, Serial No. 45,291

Term of patent 14 years

(Cl. D14—3)

FIG. 1

FIG. 2

FIG. 3

FIG. 4

FIG. 5

FIG. 6

Fig. 1 is a perspective view of an earthmoving tractor and pusher combination, embodying my new design;

Fig. 2 is a left side view, the side opposite being substantially the same;

Fig. 3 is another perspective view;

Fig. 4 is a front view;

Fig. 5 is a rear view; and

Fig. 6 is a front view of the tractor with the dozer blade removed.

The essential features of my design reside in the portions shown in full lines.

I claim:

The ornamental design for an earthmoving tractor and pusher combination, as shown and described.
